UNITED STATES PATENT OFFICE.

CARL RICHARD HIERONYMUS, OF NEW YORK, N. Y.

DESIGN FOR A FABRIC.

SPECIFICATION forming part of Design No. 13,517, dated January 9, 1883.

Application filed November 15, 1882. Term of patent 3½ years.

To all whom it may concern:

Be it known that I, CARL RICHARD HIERONYMUS, of New York, in the county and State of New York, have invented a new and original Design for a Fabric, of which the following is a specification.

The accompanying drawing represents a face view of my new design.

This invention relates to a new ornamentation of woven fabric; and it consists in forming lines therein, as hereinafter described.

a b are parallel lines recurring at regular intervals, and spaced at about equal distances

apart—that is to say, the spaces between the lines *a b* are about the same as those between the lines *b a*. Between every pair of lines *a b*, and parallel with them, are shorter lines *c d*, and alternating with them are, between the lines *b a*, short lines *e f*, as shown.

I claim—

The design for a fabric, composed of the lines *a b c d e f*, substantially as shown.

CARL RICHARD HIERONYMUS.
